Primary Examiner — George A Bugg*Assistant Examiner* — Tamara L Hahn(74) *Attorney, Agent, or Firm* — Foley & Lardner LLP(57) **CLAIM**

The ornamental design for a pallet, as shown and described.

DESCRIPTION

FIG. 1 is a front perspective view of a pallet;

FIG. 2 is a front view of the pallet, the rear view being a mirror image thereof;

FIG. 3 is a right side view of the pallet, the left side view being a mirror image thereof;

FIG. 4 is a top view of the pallet; and,

FIG. 5 is a bottom view of the pallet.

The broken lines in the drawings depict portions of the pallet that form no part of the claimed design.

1 Claim, 4 Drawing Sheets(56)
